UNITED STATES PATENT OFFICE

ARTHUR O. AUSTIN, OF BARBERTON, OHIO, ASSIGNOR, BY MESNE ASSIGNMENTS, TO THE OHIO BRASS COMPANY, OF MANSFIELD, OHIO, A CORPORATION OF NEW JERSEY.

MEANS FOR RAISING THE FLASH-OVER VOLTAGE OF BUSHING INSULATORS.

Application filed August 3, 1922. Serial No. 579,348.

This invention relates to insulator bushings for transformers, switches, roofs, walls or other structures thru which a high potential conductor passes and from which it is insulated. The invention has for its object the raising of the voltage at which flash-over will occur between the conductor and the external support for the bushing for any given type of bushing without changing the 10 construction of the bushing itself.

The invention is exemplified in the combination and arrangement of parts shown in the accompanying drawings and described in the following specification, and is more 15 particularly pointed out in the appended claims.

In the drawings:

Fig. 1 is an elevation with parts in section showing one form of the invention.

20 Fig. 2 is a similar view showing a different form.

Fig. 3 is a similar view showing another modification.

25 Fig. 4 is a part elevation and part section showing still another different form of the invention.

In Fig. 1 the numeral 10 designates a conductor which extends thru a supporting wall or plate 11, such as the cover of a transformer housing and from which the conductor is insulated by a bushing 12. The bushing may be composed of one or more sleeves 13 and be provided with suitable petticoats 14 of any well known and approved form. 30 A supporting flange 15 is cemented to the insulator 12 and rests upon the support 11 to which it is attached. Suspended from the support 11 by hooks 16 is a ring 17 of dielectric material such as porcelain. The ring 17 is U-shaped in cross section and is provided with a fitting 18 cemented or otherwise secured thereto, which is engaged by the hooks 16. The interior of the member 17 is provided with a coating 19 of conducting material. The surface may be sanded and electro-plated or may be otherwise covered with a metallic coating forming a conducting surface within the member. A portion of the inner surface of the outer flange may be left 45 uncoated adjacent the edge of the flange as shown at 20 to avoid danger of flash-over from this point. The supporting hook 16 forms electrical contact with the coating 19

so that the inner surface of the member 17 will be at the same potential as the support 11. 55

In the operation of bushings and other insulators where alternating current is used, the charging current for the insulator normally flows out from the terminals over the 60 surface of the insulator. These currents reduce the flash-over voltage since they operate as conductors shunting portions of the insulator surface. Since the charging currents are heaviest near the terminals their shunting effects will be greatest at these points. 65

In the present invention, charging current is supplied to the insulator at points removed from the terminal 11 in order to decrease the amount of charging current that would 70 otherwise flow over the insulating surface. By means of the supporting hooks 16 and the metallic coating 19 the potential of the support 11 is carried downwardly along the bushing 13 to points removed from the support. 75 The coated surface 19 acts as a condenser element for supplying current to the insulator members 13. The dielectric 17 interposed between the covering 19 and the conductor 10 resists the tendency to flash-over between the conductor and the coating 19 which would otherwise exist because of the decreased path from the support to the conductor produced by the presence of the conducting surface 19. The surface 19 also 80 acts as a flux distributor and decreases the concentration of the electro-static flux which would otherwise be present at the support 11. This distribution of the flux helps to overcome the tendency to flash-over which is 85 present where concentration of electro-static flux is found. While the coating 19 is shown as directly connected electrically to the support 11 of the conducting material, this direct connection is not essential to beneficial 90 operation since, even if there were a break in the continuity of the conducting connection, the member 19 would be charged as a condenser element or by streamers jumping the intervening gap, if it were a short air 95 gap. It will be seen that the conductor coating 19 within the dielectric member, being thin and flexible, will in no way interfere with the expansion and contraction of the member 17 due to temperature changes, as 100 would be the case if a solid metal member 105

were cemented or otherwise rigidly secured within the member 15. It will be apparent that flux distributing members may also be connected with the conductor 10 at the ends 5 of the bushings. Such distributing members are shown at 20, 21 and 22 in Fig. 2, of the drawing. These members comprise dielectric plates turned backwardly at their outer edges and having their surfaces coated with 10 a plating of conducting material shown at 23, 24 and 25 respectively.

In Fig. 2 the insulator bushing comprises a hollow dielectric member 26 passing thru a support 27 by which it is carried and provided with suitable flanges or petticoats 28 on its upper end. A conductor 29 passes thru the interior of the bushing. Surrounding the bushing 26 and supported by the plate 27 are elements of a current transformer 20 comprising an iron core 30 and a conductor winding 31. The winding 31 is connected with lead wires 32 by means of which the current from the transformer may be carried to any desired instrument. 25 Transformers of this nature are used in connection with bushings for operating relays or for connection with instruments to indicate the amount of current flowing in the main conductor 29, or for other purposes 30 requiring relatively small current values. A housing 33 encloses the transformer elements and is supported by the plate 27. The housing 33 is preferably made of conducting material such as sheet metal. A 35 dielectric ring U-shaped in cross section is shown at 34 interposed between the housing 33 and the bushing 26, and covering the housing on the side toward the adjacent end of the bushing. The ring 34 is suitably 40 supported by a bracket 35 connected with the supporting plate 27. In this arrangement the metal of the current transformer constitutes the conductor member for supplying charging current and for controlling 45 electro-static flux. The shell 33 being enclosed in the dielectric member 34 operates in a manner similar to the metallic coating 19 in the form of invention shown in Fig. 1.

As previously employed current transformers used in connection with bushings have operated to decrease the flash-over value of the bushing, but by the present invention not only is this objection overcome but the transformer may be employed to actually increase the flash-over value.

In Fig. 3 there is shown the application of a current transformer 36 to a bushing 37 of the type shown in Fig. 1. The transformer coil is covered by a casing 38 which forms a ring encircling the bushing and which is U-shaped in section to receive the coil. A dielectric ring 39 encloses the case 38 and is cemented or otherwise secured to a bracket ring 40 carried by the supporting plate 41. The bushing is supported on the

plate 41 by a suitable fitting 42 cemented to the bushing in the usual manner.

In Fig. 4 there is shown a multiple sleeve type of insulator bushing having a hollow conductor 43 extending therethru. The bushing comprises a plurality of straight tubular members 44 of dielectric material and a pair of cover members 45 and 46 of similar material, enclosing the members 44. The cover members 45 and 46 are carried by suitable fittings 47 and 48 which are connected to one another by bolts 49, the member 47 being provided with a flange 50 for securing it to the plate or wall thru which the bushing passes. A metallic plate 51 is interposed between the members 47 and 48 and projects into the interior of the housing formed by the members 45 and 46. The plate 51 carries a current transformer core 52 which is provided with a cylindrical metal shield 53 interposed between the transformer core and the outermost tubular member 44. Supported on the pins 54 projecting toward the ends of the bushing are dielectric covers 55 and 56 which serve a purpose similar to that of the dielectric rings 34 and 39 previously described. It will be seen from Fig. 4 that the pins 54 fit loosely in the dielectric members 55 and 56, leaving the members free to expand and contract with temperature changes. The ends of the conductor 43 may be provided with insulating flux control members 57 and 58 to provide improved flux distribution and assist in decreasing the flash-over voltage of the bushing.

The insulated shields are particularly valuable for protecting surfaces under oil adjacent to electrode surfaces under high stress. The streamers which may start from the electrode over the adjacent surface may cause damage due to the heat generated. The insulated shields may be used to reduce these streamers so that a higher voltage may be applied without causing damage.

The insulated shields or controls may be used to prevent damage by eliminating the surface streamers but increased flash-over usually results.

Bushings which normally have rather low flash-overs owing to heavy shunting streamers may be greatly improved by the application of the insulated controls.

The controls may be used either inside or outside of the bushing to eliminate destructive or dangerous potential gradients.

Interior and exterior members may be used in conjunction where convenient.

When used on the outside of transformer or switch bushings the danger of the charging current igniting any gas is greatly reduced. This eliminates the necessity of covering the surface of the bushing by a metal shield between the level of the oil and the cover of the transformer or switch.

Since the metal shield may be eliminated

a shorter and cheaper bushing may be used and if there is any surface above the oil it is capable of furnishing a high degree of insulation.

5. This is particularly valuable in oil switches where the surface above the oil may be in fairly good condition compared to the surface below the oil which may become very dirty from discharges.

10. I claim:

1. In combination, a tubular insulator, a conductor extending through said insulator, a support secured to the exterior of said insulator between its ends, a dielectric member of fragile material surrounding said insulator adjacent the outer face thereof, said member being U-shaped in cross section and open at one side to permit assembly of conducting material therein after formation of

15. said dielectric member, and conducting material within said dielectric member arranged to leave the inner walls of said dielectric member free to move by expansion or contraction, the conducting material within

20. said dielectric member extending to a position between said support and one end of said insulator, the closed end of said dielectric member being disposed between the conducting material within said dielectric member and said end of said insulator.

25. 2. In combination, a bushing insulator having a conductor extending therethrough and having an exterior support of conducting material between its ends, an element of conducting material connected with said conductor at a point beyond one end of said bushing and extending toward said support, and a dielectric cover for said element disposed about the portion thereof directed

30. 45 away from said conductor for decreasing danger of flash-over therefrom while permitting said element to form part of a charging current circuit for said bushing.

3. In combination, a bushing insulator having a conductor extending therethrough and having an exterior support of conducting material between its ends, an element of conducting material connected with said conductor at a point beyond the end of said 50 insulator and extending toward said support, a dielectric covering for said element, a member of conducting material connected with said support and extending toward one end of said bushing to a point nearer said end than any portion of said support, and a dielectric covering disposed about the portion of said last-named member of conducting material farthest removed from said support.

4. In combination, a tubular insulator, a conductor extending through said insulator, a support of conducting material for said insulator positioned between its ends, flux controls at the ends of said insulator connected with said conductor and extend-

ing therefrom toward said support, the portions of said controls nearest said support being covered with dielectric material interposed between said controls and said support, a member of conducting material extending toward an end of said insulator from said support to a point nearer said end of said insulator than any portion of said support, and a dielectric covering for said member of conducting material interposed between said member and said end of said insulator.

5. In combination, a bushing insulator, a current transformer element encircling said insulator between its ends, a casing of conducting material for said transformer element, and a dielectric covering for said casing interposed between the casing and the end of said bushing, said transformer casing constituting means for feeding charging current to the surface of said insulator.

6. In combination, a bushing insulator, a conductor extending therethrough, a current transformer element encircling said insulator between its ends, a casing of conducting material for said transformer element, a dielectric covering for said casing interposed between the casing and the end of said bushing, and flux control members connected with said conductor at the ends of said bushing and having portions thereof directed toward the middle of said bushing and covered with dielectric material interposed between said members and the middle of said bushing, said transformer casing and flux control members constituting means for feeding charging current to the surface of said bushing insulator.

7. In combination, a bushing insulator having a conductor extending therethrough, a support of conducting material for said insulator between its ends, a current transformer casing of conducting material carried by said support and electrically connected therewith and projecting therefrom toward one end of said insulator, and a covering of dielectric material interposed between said transformer casing and said end of said insulator to resist flash-over from said conductor to said transformer casing and to enable the material of said transformer casing to act as an element of a condenser to supply charging current to said insulator.

8. In combination, a bushing insulator having a conductor extending therethrough, an exterior support of conducting material for said insulator between its ends, a current transformer core carried by said support and encircling said insulator, a metallic housing for said transformer core extending from said support toward one end of said insulator, and a covering of dielectric material interposed between said housing and said end of said insulator to resist flash-

- over from said conductor to said housing and to raise the flash-over voltage of said bushing insulator by decreasing leakage currents on the surface of said insulator, said 5 transformer core and housing constituting with said covering of dielectric material the elements of a condenser for feeding charging current to said insulator.
9. In combination, a bushing insulator 10 having a conductor therethrough, a support through which said insulator extends, a current transformer element surrounding said insulator at one side of said support, a housing of conducting material for said trans- 15 former element connected with said support, and a hollow ring of dielectric material covering said housing and interposed between said housing and the end of said insulator, said transformer element and housing con- 20 stituting with said ring the elements of a condenser to feed charging current to said bushing insulator.
10. An insulator bushing comprising a tubular dielectric member having a conductor 25 extending therethrough, a support of conducting material for said dielectric member intermediate the ends thereof, a current transformer element of conducting material encircling said tubular dielectric member 30 between the ends thereof, and a dielectric ring U-shaped in cross section supported on and enclosing the extremities of said trans- 35 former element away from said support.
11. An insulator bushing comprising a tu- 40 bular dielectric member having a conductor extending therethrough, a current trans- 45 former element of conducting material in the shape of a ring surrounding said dielectric member between the ends thereof, a sup- port of conducting material for said trans- 50 former element, means for supporting said tubular member from said transformer ele- 55 ment, and dielectric cover rings U-shaped in cross section fitting over the edges of said transformer element to minimize discharge 60 from said transformer element.
12. An insulator bushing comprising a tubular dielectric member having a conductor extending therethrough, a transformer 65 element of conducting material in the form of a ring surrounding said dielectric member between the ends thereof, means for securing said dielectric member to the interior of said ring, a support for said ring dis- 70 posed outside thereof, dielectric coverings for the edges of said ring, and dielectric casing members enclosing said tubular dielectric member and said transformer ele- 75 ment.
- 60 13. A dielectric bushing comprising a plurality of concentric tubular dielectric members having a conductor extending through the innermost member, means for supporting said tubular members and conductor, 80 a transformer element of conducting mate- 85 rial surrounding said tubular members, a dielectric housing for said tubular members and transformer element, said housing being made in separate parts, a supporting ring of conducting material for said housing, means carried by said supporting ring and extending between the parts of said housing and engaging said transformer element for supporting said transformer element and for 85 electrically connecting said transformer element with said supporting ring, and dielectric coverings interposed between the edges of said transformer element and the ends of said bushing.
14. An insulator bushing comprising a dielectric tubular member having a conductor extending therethrough, a current transformer element of conducting material in the form of a ring surrounding said tubular member between the ends thereof, pins projecting from the edges of said ring, and rings of dielectric material U-shaped in cross section supported by said pins, said pins ex- 90 tending into the openings in said U-shaped members.
15. A bushing insulator comprising a tubular dielectric member, a conductor extending through said member and projecting from opposite ends thereof, a support of conducting material secured to said member be- 95 tween the ends thereof, a flux control mem- 100 ber of conducting material electrically connected with said support and extending therefrom toward one end of said insulator to a point nearer the end of said insulator than said support, a dielectric covering dis- 105 posed between said flux control member and said end of said insulator, and a two-part casing of dielectric material enclosing said insulator and flux control member and carried by said support.
16. A bushing insulator comprising a tubular dielectric member, a conductor ex- 110 tends through said member and projecting from the ends thereof, a support of conducting material connected with said tubular dielectric member between the ends thereof, a housing of conducting material for a cur- 115 rent transformer element encircling said tubular dielectric member between the ends thereof and supported by and electrically connected with said support, said housing extending toward one end of said tubular dielectric member beyond said support, a covering of dielectric material interposed be- 120 tween said transformer housing and said end of said tubular dielectric member, and a two-part dielectric casing carried by said support and enclosing said tubular dielectric member and said current transformer hous- 125 ing.
17. A bushing insulator, a conductor ex- 130 tends through said insulator, and a sec-

ondary winding disposed within said bushing insulator and forming with said conductor a current transformer.

18. A bushing insulator, a conductor extending through said insulator, a secondary winding of a current transformer disposed within said insulator, and a baffle of dielectric material interposed between said conductor and secondary winding.

19. A bushing insulator, a support for said insulator connected thereto between the ends thereof, a current transformer element disposed within said insulator and electrically connected with said support, and a primary conductor extending through said insulator.

20. A bushing insulator, an external support for said insulator disposed between the ends thereof, a conductor extending through said insulator, a secondary current transformer winding disposed within said insulator and surrounding said conductor, and a

dielectric covering for said transformer winding interposed between said winding and the end of said insulator.

21. A bushing insulator, an external support for said insulator disposed between the ends thereof, a conductor extending through said insulator, a secondary current transformer winding disposed within said insulator and surrounding said conductor, a dielectric baffle interposed between said conductor and secondary winding, a magnetic core for said winding electrically connected with the external support for said insulator, and a dielectric covering for said winding and core interposed between said winding and the end of said dielectric baffle.

In testimony whereof I have signed my name to this specification on this 29th day of July, A. D. 1922.

ARTHUR O. AUSTIN.
